UNITED STATES PATENT OFFICE.

WILLIAM J. MACKLE, OF ST. LOUIS, MISSOURI, ASSIGNOR TO THE J. G. BRILL COMPANY, OF PHILADELPHIA, PENNSYLVANIA, A CORPORATION OF PENNSYLVANIA.

PASSENGER-CAR.

No. 918,344.

Specification of Letters Patent. Patented April 13, 1909.

Application filed May 11, 1908. Serial No. 432,008.

To all whom it may concern:

Be it known that I, WILLIAM J. MACKLE, a citizen of the United States, residing at St. Louis, Missouri, have invented certain improvements in Passenger-Cars, of which the following is a specification.

The object of my invention is to provide a passenger car with a doorway and a single sliding door which can be used in the type of car known as the "pay-as-you-enter" car, in which the passenger boards the car, pays his fare while on the platform before entering the car, and he can make his exit from either end of the car. This object I attain in the following manner, reference being had to the accompanying drawings, in which:—

Figure 1, is a sectional plan view of one end of a car illustrating my invention and showing the door closing the exit passageway; Fig. 2, is a view illustrating a portion of Fig. 1, showing the door entirely closing the passageway; and Fig. 3, is a view similar to Fig. 2, showing the door closing the entrance passageway.

25 A is the body of the car.

B is the platform and C the transverse partition separating the platform from the body of the car.

c is the doorway, which is divided into two sections by the rail F which separates the egress portion b of the platform from the ingress portion b'. This rail has a permanent section f and a swinging section f' which can be thrown either to lock against the post E or 35 to hang down, as desired.

D is a single door of such a width as to extend when in the mid position from one edge of the doorway c to the other, as illustrated in Fig. 2, so as to close both the exit and the 40 entrance to the car. The door is adapted to the channels c—c' in the partition C at each edge of the doorway and it is adapted to travel in the ordinary ways common to this type of door so that it can be moved either 45 into the position in which a portion of the door is in the channel c', the other portion of the door closing the exit from the car, as shown in Fig. 1, or it can be moved to a central position as shown in Fig. 2, closing both the exit 50 and the entrance passageways or it can be moved to the position shown in Fig. 3, one portion of the door entering the other chan-

nel c', the other portion closing the entrance passageway. Thus it will be seen that while a single door is used, the passageways are under the complete control of the conductor. If the doors are used at both ends of the car and it is desired to provide an exit for passengers at the front end, then the door is moved into one of two positions, Figs. 1 or 3, 60 allowing the passenger to alight from the car at either side according to the regulations of the road.

Doors or gates may be provided at each side of the platform to close the sides not in use. These gates or doors can be of any suitable form and hung in any manner desired.

I claim:

1. The combination in a passenger car, of 70 a body portion, a platform, a partition separating the two, said partition having a wide doorway, a guard dividing the doorway so as to form ingress and egress passageways, a single sliding door adapted to the doorway 75 and of such a width that when in the central position it will close the doorway and when in one position at one side or the other of the doorway it will close the passageway on that side of the guard. 80

2. The combination in a passenger car of a body portion, a platform, a transverse partition separating the platform from the body portion, said partition having a central wide doorway and having channels at each side of 85 the doorway, a wide sliding door, a rail dividing the platform into ingress and egress sections, said rail terminating at or about the center of the doorway, the said door being of such a width that when in a central position it will close the doorway and when moved to one side, part of the door will enter the channel on one side and close the ingress passageway and when moved to the other side will enter the other channel and close the 95 egress passageway.

In testimony whereof, I have signed my name to this specification, in the presence of two subscribing witnesses.

WILLIAM J. MACKLE:
